UNITED STATES PATENT OFFICE.

CHARLES J. RATEIKE, OF CHICAGO, ILLINOIS, ASSIGNOR TO ANSON MARK AND CLAYTON MARK, COPARTNERS DOING BUSINESS AS MARK MANUFACTURING COMPANY, OF CHICAGO, ILLINOIS.

PIPE-FITTING.

1,232,972.

Specification of Letters Patent. Patented July 10, 1917.

Application filed March 18, 1915. Serial No. 15,289.

To all whom it may concern:

Be it known that I, CHARLES J. RATEIKE, a citizen of the United States, residing at Chicago, Cook county, Illinois, have invented new and useful Improvements in Pipe-Fittings, of which the following is a specification, reference being had to the accompanying drawings, in which:

Figure 1 is an elevation of a plate blank; 10 Figs. 2, 3 and 4 are elevations showing successive steps in the reduction and elongation of a blank or shell preliminary to shaping it into the desired fitting; Fig. 5 shows a blank which has been reduced by an operation 15 preliminary to forming a T; Fig. 6 is a bottom view of the form shown in Fig. 5; Fig. 7 is an elevation of a formed T, and Fig. 8 is a bottom view thereof.

My invention relates to pipe fittings and 20 consists in the formation of fittings from plate blanks or cup-shaped shells, so that such fittings are of uniform strength and thickness. My invention also relates to the various features which I shall hereinafter 25 describe and claim.

Referring to the drawings, in which I have shown my invention applied to a T, the plate shown in Fig. 1 may be reduced, by a drawing operation, to the form of a 30 cup-shaped shell, shown in Fig. 2. By subsequent drawing operations the shell is reduced until it is of approximately the diameter desired for one of the arms 2 of the finished product, as is shown in Fig. 4. The 35 blank is then placed with its arm or end 2 supported in other suitable dies, which flatten its top surface and bulge its sides 3 and 4 to form the other arm or arms of the fitting. Its body portion 5, as is shown in 40 Figs. 5 and 6, will bulge outwardly around the axis of the arm 2 and will assume a mushroom shape. It is then reduced to the form shown in Figs. 7 and 8, by striking the blank on its side, which trues or shapes 45 the projections 3 and 4 to the desired form. The fitting may then be completed by aperturing its ends 3 and 4, and by threading.

I have found that in carrying out my invention I am able to construct a pipe fitting 50 in which the metal is maintained of substan-

tially uniform thickness throughout, and, due to the fact that the ends are not apertured until the form of the fitting is substantially complete, they are of substantially the same strength as the remainder of 55 the fitting, and need no squaring at the completion of the forming operations. My invention has also enabled me to reduce very greatly the number of operations necessary to form the T, and has accordingly decreased the expense of dies, etc.

The terms and expressions which I have employed herein are used as terms of description and not of limitation, and I have no intention in the use of such terms and 65 expressions of excluding any equivalent for the features shown and described, but recognize that various modifications are possible within the scope of the invention claimed.

What I claim is:

1. The process of making a pipe fitting, which consists in taking a plate, forming it into a cup-shaped blank having substantially the diameter of one arm of the completed article, then swaging the exterior of 75 the blank, while its interior is unsupported, and causing its sides to bulge, then shaping the bulging sides to the desired form, and aperturing them.

2. A process of making a pipe fitting 80 which consists in taking a shell of cup-shaped form, applying compression to the exterior of the top and bottom of said shell, meanwhile supporting its bottom end and while its interior is unsupported, and thereby causing its sides to bulge outwardly and circumferentially, applying compression to exterior parts of the bulged-out portion, and thereby forming the bulged-out portion to cylindrical form, and aperturing the 85 cylindrical portion so formed.

3. The process of making a pipe fitting, which consists in shaping a shell of cup-shaped form by supporting the open end of the shell, applying compression upon the 95 exterior of its closed end while its interior is unsupported, whereby the sides of the shell will bulge outwardly until it assumes a mushroom-like form, applying compression to the exterior of the bulged-out por-

tion, to shape such portion to the desired form, and aperturing the end of the portion so shaped.

4. The process of making a pipe fitting, 5 which consists in shaping a cup-shaped shell by externally applied compression, by altering the diameter of a portion of the shell, and forming one portion of mushroom-like

form and the other portion of substantially the diameter of one arm of the completed 10 fitting, then shaping the mushroom-like portion and aperturing it.

CHARLES J. RATEIKE.
